SEALING CAP

Gerhart Weiss, Jackson Heights, N. Y.

Application September 12, 1951, Serial No. 246,183.

7 Claims. (Cl. 220—44)

My invention relates to an improved sealing cap for releasably sealing containers which are partially or entirely filled with air or other gases.

The sealing cap has a central diaphragm portion, an integral annular outer portion, and a flexible annular skirt member which is positioned below this outer portion. The outer portion and the skirt member are connected together adjacent their inner edges. I also provide a radially extending groove in the under surface of said outer portion.

I place the sealing cap on a container, with the outer portion and the skirt member overlying the rim of said container. The diaphragm portion may then be forced downwardly, thereby pressing the skirt member against the rim of the container and compressing the air therein.

However, the compressed air forces the part of the skirt member beneath the outer portion groove, upwardly into said groove. This permits the escape of air from the container until its pressure is equalized with that of the atmosphere.

When the downward force on the diaphragm portion is released, it moves upwardly to its normal position. This creates a partial vacuum in the container, as a result of which the cap is sealed in place.

The cap may also be mounted on a wall or other member so as to support an object which may be attached to said cap.

The improved cap serves as an excellent sealing means because of the provision of the groove, which allows the escape of a maximum amount of air from the container when the diaphragm portion is pressed downwardly.

Another advantage of my invention is that the cap may be used to seal containers having rims of varying diameters.

Other advantages of my invention are that it may be readily assembled from two molded plastic members, and that it may be easily applied to and removed from a container.

Other objects and advantages of my invention will become apparent from the following description, in conjunction with the annexed drawings, in which preferred embodiments are disclosed.

In the drawings,

Fig. 1 is a top plan view of my improved sealing cap as applied to the open top of a container.

Fig. 2 is a section on line 2—2 of Fig. 1.

Fig. 3 is an enlarged section on line 3—3 of Fig. 1, showing the cap in its sealing position on the top of the container, the bottom of the container being broken away.

Fig. 4 is a view similar to Fig. 3, showing the center portion of the cap depressed, the cap reaching its sealing position of Fig. 3 when the center portion is released.

Fig. 5 is a vertical section showing another embodiment of the sealing cap, said cap being mounted on a container whose bottom portion is broken away.

Fig. 6 is a fragmentary bottom plan view of the sealing cap shown in Fig. 5.

2

Fig. 7 is a vertical section through another embodiment of the sealing cap, said cap being also shown as applied to a container the bottom part of which is broken away.

The drawings show a working model of the cap and are drawn to scale. Figs. 1 and 2 are drawn in 1:1 scale, and Figs. 3 and 4 are drawn in 2:1 scale. Reference is made to the drawings to complete this description of the cap.

In the drawings, my improved sealing cap is shown mounted on the preferably circular rim 14a of a jar-like container 14. Container 14 is shown in an upright position, and I assume this to be its orientation in the description, although it will be apparent that the cap may be applied to container 14 when it is held in any position.

The seal cap comprises a central diaphragm portion 10, an annular outer portion 11 which is integral with this center portion 10, and an annular skirt member 13 which is positioned below this outer portion 11 and attached thereto. I optionally provide a depending circumferential and peripheral flange 12 which is integral with said outer portion 11.

The sealing cap is normally substantially upwardly convex, as shown in Figs. 1—3. The inner edge of outer portion 11 is positioned above the plane of the outer edge 25 of outer portion 11.

Center 10 optionally and preferably has a plurality of alternate concentric ridges 18 and grooves 19 in the upper face thereof. Each ridge 18 has a complementary groove 18a beneath it in the lower face of center portion 10; and each groove 19 has a complementary ridge 19a beneath it in the lower face of center portion 10, so that center portion 10 is corrugated. The outer wall 20 of the outermost groove 19 slopes outwardly and upwardly above the outermost ridge 18, with the upper edge of said wall 20 serving as the inner edge of outer portion 11.

This annular outer portion 11 slopes somewhat downwardly, so that its outer edge is disposed in a plane below the plane of its inner edge.

I provide a groove 15 in the under surface of portion 11, which preferably extends radially between the inner and outer edges of said portion 11. The forming of this groove 15 results in the forming of a corresponding raised portion 15a in the upper surface of outer portion 11.

Skirt member 13 preferably has approximately the same dimensions as annular portion 11. The inner edge of said member 13 preferably abuts the inner edge of the under surface of portion 11 and is secured thereto by glue or other suitable means. As a result most of skirt member 13 is unattached to the outer section of the body portion 11.

Skirt member 13 is preferably made, by molding or other suitable means, from a vinylite or other suitable plastic material which is pliable and resilient and optionally slightly stretchable. Center portion 10, outer portion 11 and flange 12 are preferably made in one piece, by molding or other suitable means, from a vinylite or other suitable plastic material which is somewhat bendable and which is resilient, but which is relatively rigid compared to the material from which skirt member 13 is formed.

Fig. 3 shows the sealing cap in its normal position when mounted on container rim 14a. Center portion 10 is disposed within the circumference of rim 14a and above the plane thereof. The inner edges of annular portion 11 and skirt member 13 and the inner end of groove 15 are disposed within the circumference of rim 14a. The outer edges of annular portion 11 and skirt member 13, the outer end of groove 15, and flange 12 are disposed outside the circumference of rim 14a.

As is also shown in Fig. 3, the portion of skirt member 13 which overlies rim 14a substantially rests there-

on. This is because the portion of skirt member 13 intermediate its inner and outer edges is normally spaced from annular portion 11, the material of which member 13 is formed being sufficiently stiff normally to maintain this relationship of parts 11 and 13. It is preferred that skirt member 13 substantially abut approximately the entire area of rim 14a.

After the cap has been placed on container 14 in the manner described above, the cap may be manually manipulated so as to seal it releasably upon rim 14a. I exert force on center portion 10 so as to bend it downwardly in the direction of arrow 16 to its position of Fig. 4. In this position of Fig. 4, center portion 10 is substantially downwardly convex. When center portion 10 moves from its position of Fig. 3 to its position of Fig. 4, it bends evenly along the various grooves 19.

The force thus directed on the cap in the direction of arrow 16 presses skirt member 13 firmly against rim 14a and compresses any air which may be present in the space bounded by the inner walls of container 14 and the sealing cap.

However, annular portion 11 is not pressed downwardly upon that part of skirt member 13 which underlies groove 15. The compressed air in container 14 forces this part of skirt member 13 upwardly into groove 15, this movement being aided by the slight stretchability of said skirt member 13. Air flows out of container 14, in the direction of arrow 17, through the resulting space between rim 14a and the part of skirt member 13 which has been forced upwardly within groove 15. This flow of air continues until the pressures within and outside container 14 are equalized. The raised portion 13 then tends, as a result of its resiliency, to return to its position of abutment with rim 14a.

When the downward force on center portion 10 is released, it automatically moves upwardly to its normal position of Fig. 3. This creates a partial vacuum in container 14, as a result of which the cap remains firmly seated upon rim 14a.

It is apparent that the cap may be readily seated upon containers having mouths of varying diameters, so long as annular portion 11 and skirt member 13 are positioned above rim 14a. Also, the cap may be readily unsealed since it is not mechanically secured to container 14. Also, because of the channel formed for the escape of air, as a result of the provision of groove 15, the cap may be sealed upon a container which has a large volume of air compared to the air located between the cap and the plane of rim 14a.

It is also apparent that my device may be applied directly to a wall or other surface so as to support an article which may be attached to said cap. In this case, flange 12 may be omitted.

It is also apparent that my device includes a central diaphragm portion 10, an outer portion 11 which may be made of any suitable relatively rigid material, and an annular skirt member 13 which is positioned beneath said outer portion 11 and attached thereto along the entire inner edge of said skirt member 13. Outer portion 11 has a groove 15 in the under surface thereof above skirt member 13. When the sealing cap is placed upon jar-like container 14 with outer portion 11 and skirt member 13 overlying the entire rim 14a and with groove 15 extending between the inner and outer edges of said rim 14a, the rigidity of outer portion 11 results in skirt member 13 being firmly seated on rim 14a when a downward force is exerted on diaphragm 10. This diaphragm 10 is made of such material that it is adapted to be depressed by such a downward force. Skirt member 13 is made of a resilient and at least slightly stretchable material, so that the resulting compressed air in container 14 can force that portion of said skirt member 13 beneath groove 15 upwardly into said groove 15 so as to form the desired opening for the escape of air. This

resiliency of skirt member 13 causes it to tend to move back toward rim 14a when the air pressure inside and outside container 14 is equalized. The material of diaphragm 10 has further properties, as a result of which said diaphragm 10 moves upwardly when said downward force thereon is released.

In certain applications, I prefer to use a diaphragm member which is made of rubber or a similar flexible and resilient material, instead of the type of diaphragm 10 which is shown in Figs. 1 to 4. Such a modification is shown in Fig. 7. In this embodiment, I provide a rigid annular outer portion 21 which corresponds to the annular member 11 of the first embodiment. I provide a normally convex diaphragm member 22 which corresponds to the diaphragm member 10 of the first embodiment. I also provide a gasket member 23 which corresponds to the skirt member 13 of the first embodiment. However, in this embodiment, I prefer to make diaphragm 22 and gasket 23 integral and of the same material:

As is shown in Fig. 7, diaphragm 22 is normally upwardly convex and may be made of rubber or any other suitable flexible and resilient material. The bottom portion of the wall of diaphragm 22 extends through the central opening in the rigid annular member 21 and frictionally abuts the edge of said opening. Gasket member 23 is annular in shape and is preferably an outwardly extending flange which is integral with the bottom of said diaphragm 22. This gasket member 23 is positioned proximate to the lower face of outer member 21. I prefer to secure the upper face of gasket 23 to said lower face of member 21 around the entire circumference of said members 21 and 23, but preferably only at the respective areas adjacent the respective inner edges thereof. As a result, the outer portion of gasket 23 is not connected to member 21. The connection between members 21 and 23 may be by gluing or any other suitable means.

I provide diaphragm 22 with a further integral, outwardly extending annular flange 24 which frictionally abuts the upper face of outer member 21 and which is secured thereto by gluing or any other suitable means.

In this embodiment, I also provide one or more air vents which are all similar in function to the groove 15 in the first embodiment. One such air vent is shown in Fig. 7 and comprises a radially extending groove 25 in annular member 21. This provides a space into which a portion of gasket 23 can be raised during operation of the sealing cap.

Optionally, I provide annular member 21 with a flange 12, as in the first embodiment.

The operation of the embodiment of Fig. 7 is the same as the operation of the first embodiment. Fig. 7 corresponds to Fig. 3, and it is apparent that when the sealing cap is placed upon container 14 and diaphragm 22 is depressed, air will be forced out of container 14 in the manner illustrated in Fig. 4.

Another embodiment is shown in Figs. 5 and 6. The first two embodiments disclose a sealing cap which is primarily designed to evacuate just enough air from a partially filled container to provide a vacuum which will maintain the cap in place. Sometimes, it is desirable in addition to pump the greater amount of the air out of the container.

The embodiment of Figs. 5 and 6 provides a cap which can be placed on top of the container 14, which can be operated so as to evacuate most of the air from said container 14, and which will then be automatically sealed in place.

The cap shown in Figs. 5 and 6 comprises a rigid plate 30. Optionally, said plate 30 may have an annular outer portion 31 and an integral cup-shaped center portion 32 whose bottom wall 32a is positioned below the plane of annular portion 31 under normal operating conditions.

I provide the usual flexible gasket 33, which is annular in shape and which is positioned below annular portion 31, in the manner clearly shown in Fig. 5. Optionally, gasket 33 may be secured to annular portion 31.

Optionally, also, I provide a depending cylindrical flange 34 which is integral with the outer edge of plate 30. Of course, the cap is mounted upon container 14 in the usual manner with flange 33 resting upon the top of said container 14 and with flange 34 positioned outside said container 14.

I provide the center of cap portion 32a with an opening and a suitable non-return check valve mounted within said opening. I prefer to provide such an opening 35 of inverted frustro-conical shape in order to serve as a suitable seat for a valve V. Said valve V has an inverted frustro-conical upper portion 36 which is adapted to sit upon the seat provided by the wall of said opening 35. The bottom of said valve head 36 is provided with a depending shank 37 in which is mounted a suitable transverse stop pin 38 which prevents upward removal of the valve V through opening 35.

In order to evacuate the air from container 14 after the sealing cap has been mounted thereon in the manner shown in Fig. 5, I provide a suitable suction cap means which is disposed within the cup portion 32 of plate 31. In Fig. 5, such evacuating means is shown as a conventional suction cap 39 which may be made of rubber or other suitable material. This cap 39 is normally generally upwardly convex in shape, and the bottom of its wall is positioned upon cap portion 32a and spaced from the side wall of cup 32.

It will be apparent that I may replace cap 39 by a structure similar to that shown in Fig. 1 or in Fig. 7.

In the operation of this embodiment, suction cap 39 is alternatively pressed downwardly and released a plurality of times. Each time that suction cup 39 is pressed downwardly its wall is pressed toward the side wall of cap 32, and air is evacuated from the interior space of said suction cup 39. Valve V is forced downwardly, so that valve head 36 blocks opening 35. When suction cap 39 is allowed to return to its normal position of Fig. 5, a partial vacuum is created within the interior of said suction cup 39. The pressure of the air within container 14 forces valve V upwardly until stop pin 38 abuts plate portion 32a. This opens valve V and permits air to flow from container 14 to the interior space of suction cup 39 until equilibrium is reached.

When suction cup 39 is removed, a partial vacuum has been created within container and atmospheric pressure maintains valve V in closed position. Optionally, the suction cup may be attached to plate 30 so as to make it non-removable, but the principle of operation remains the same.

In order to facilitate the removal of the sealing cup from container 14, I provide a slot 40 in flange 34, which makes it possible to insert an instrument between gasket 33 and the top of container 14, in order to break the seal.

While I have disclosed preferred embodiments of my invention and have indicated various changes, omissions and additions which can be made therein, it will be apparent that various other changes, omissions and additions may be made in my invention without departing from the scope and spirit thereof.

For example, the construction of the diaphragm member may be modified in many ways. In particular, the diaphragm member can consist of a spiral spring which is laminated between two sheets of flexible plastic, rubber, or the like. Alternatively, the diaphragm member may be reinforced by any suitable metal spring or the like.

It will be seen that according to my invention, the sealing cap may have any suitable suction diaphragm portion and suitable gasket portion, together with a rigid body portion which overlies the gasket portion and which has a suitable opening through which the diaphragm may be reached in order to operate same. The diaphragm

and the gasket may be made in one piece, which may optionally be connected to the rigid body member. Also, the diaphragm member and the gasket member may be made separately, in which case the diaphragm member is optionally and preferably secured to the body member and the gasket is also optionally secured thereto.

I claim:

1. A sealing cap comprising a central diaphragm, an annular body member which is integral with said diaphragm, said diaphragm being attached to said body member over the entire inner circumference thereof, said diaphragm and said body member being made of relatively rigid material, and an annular flexible and resilient gasket which is mounted beneath said body member and is substantially coextensive therewith with its inner peripheral edge only hermetically sealed throughout to the body member, said gasket being adapted to be clamped at its outer edge by the body member onto the rim of the container, said diaphragm being normally upwardly convex and having a plurality of substantially concentric corrugated grooves, whereby it is adapted to be moved downwardly relative to said body member from its normal position into a downwardly convex position, said diaphragm being thereby tensioned so as to be adapted to return to its normal position upon release of the downward force thereon, said body member having a radial groove in the under-surface thereof above said gasket; said sealing cap being thereby adapted to be sealed to the rim of a container by mounting said cap on said rim with said gasket resting on said rim and with said groove overlying said rim between the inner and outer edges thereof, and depressing said diaphragm whereby to create an air pressure which forces a portion of said gasket into said groove and permits the escape of air from said container through the resulting opening between said gasket and said rim, and then releasing said diaphragm, the resulting return of said diaphragm to its normal position tending to create a partial vacuum within said container.
2. A sealing cap comprising a central diaphragm, an annular body member, means hermetically sealingly connecting said diaphragm and said body member so that said diaphragm is attached to said body member over the entire inner circumference thereof, said diaphragm and said body member being made of relatively rigid material, and an annular flexible and resilient gasket which is mounted beneath said body member and is substantially coextensive therewith with its inner peripheral edge only hermetically sealed throughout to the body member, said gasket being adapted to be clamped at its outer edge by the body member onto the rim of the container, said diaphragm being normally upwardly convex and having a plurality of substantially concentric corrugated grooves, whereby it is adapted to be moved downwardly relative to said body member from its normal position into a downwardly convex position, said diaphragm being thereby tensioned so as to be adapted to return to its normal position upon release of the downward force thereon, said body member having a radial groove in the under-surface thereof above said gasket, said sealing cap being thereby adapted to be sealed to the rim of a container by mounting said cap on said rim with said gasket resting on said rim and with said groove overlying said rim between the inner and outer edges thereof, and depressing said diaphragm whereby to create an air pressure which forces a portion of said gasket into said groove and permits the escape of air from said container through the resulting opening between said gasket and said rim, and then releasing said diaphragm, the resulting return of said diaphragm to its normal position tending to create a partial vacuum within said container.
3. A sealing cap comprising a rigid annular body member, a central flexible and resilient diaphragm member which is attached to said body member over the entire inner circumference thereof, and an annular flexible and resilient gasket which is mounted beneath said body mem-

ber and is substantially coextensive therewith with its inner peripheral edge hermetically sealed throughout to the body member, said gasket being adapted to be clamped at its outer edge by the body member onto the rim of a container, said diaphragm member having a normal position in which it is upwardly convex and being stressed so as to tend to remain in said normal position, said diaphragm member being adapted to be moved downwardly relative to said body member from said normal position by the application of point force thereon to a position in which it is downwardly convex, said diaphragm member being thereby tensioned so as to be adapted to return to its normal position upon release of the downward force thereon, said body member having a radial groove in the under-surface thereof above said gasket, said sealing cap being thereby adapted to be sealed to the rim of a container by mounting said cap on said rim with said gasket resting on said rim and with said groove overlying said rim between the inner and outer edges thereof, and depressing said diaphragm whereby to create an air pressure which forces a portion of said gasket into said groove and permits the escape of air from said container through the resulting opening between said gasket and said rim, and then releasing said diaphragm, the resulting return of said diaphragm to its normal position tending to create a partial vacuum within said container.

4. A sealing cap in accordance with claim 3, said groove being sufficiently shallow and said gasket

being sufficiently resilient so that said raised gasket portion is sealed against the rim of said container, upon return of said diaphragm to its normal position, in sufficient time to maintain partial vacuum within said container.

5. A sealing cap in accordance with claim 4, in which said diaphragm is integral with said body portion, said body portion and said gasket being connected together only along their inner edges.

6. A sealing cap in accordance with claim 3, in which said diaphragm extends through the opening of said body member and is integral with said gasket.

7. A sealing cap in accordance with claim 6, in which said diaphragm has a laterally extending peripheral flange which abuts the upper face of said body member, said body member being relatively rigid with respect to said diaphragm.
